COVER FOR STORAGE BATTERIES

Robert S. Beverlin, Toledo, Ohio, assignor to The City
Auto Stamping Company, Toledo, Ohio, a corporation of Ohio

Application November 4, 1954, Serial No. 32,961

Term of patent 7 years

(Cl. D26—6)

FIG. 1.

FIG. 2.

FIG. 3.

I claim:

The ornamental design for a cover for storage batteries, as shown.
